UNITED STATES PATENT OFFICE.

AMOS DUPONT, OF CHAMPLAIN, NEW YORK.

DESIGN FOR A HANDLE FOR COMBS, KNIVES, OR SIMILAR ARTICLES.

No. 38,920.

Specification for Design.

Patented Dec. 3, 1907.

Application filed September 16, 1907. Serial No. 393,245. Term of patent 14 years.

To all whom it may concern:

Be it known that I, AMOS DUPONT, a citizen of the United States, residing at Champlain, in the county of Clinton and State of New York, have invented a certain new, original, and ornamental Design for a Handle for Combs, Knives, or Similar Articles, of which the following is a specification, reference being had to the accompanying drawing, forming part thereof.

The figure is an elevation showing the design.

I claim:

The ornamental design for a handle for combs, knives, or similar articles, as shown.

AMOS DUPONT.

Witnesses:

LOUIS G. RICHARD,
D. BERTRAND.
